UNITED STATES PATENT OFFICE.

WILLIAM H. BILBROUGH, OF ELMIRA, NEW YORK.

UNION SUIT.

1,120,892.

Specification of Letters Patent. Patented Dec. 15, 1914.

Application filed March 21, 1912. Serial No. 685,286.

To all whom it may concern:

Be it known that I, WILLIAM H. BILBROUGH, a citizen of the United States, residing at Elmira, in the county of Chemung and State of New York, have invented certain new and useful Improvements in Union Suits, of which the following is a specification.

This invention relates to garments and more particularly to that class of garments known as union suits.

The objects of this invention are to provide a garment which is simple in construction, is adapted to thoroughly cover the posterior parts of the wearer and also to serve as a suspensory.

Other objects and the features of novelty will be apparent from the following description taken in connection with the accompanying drawings, in which,

Figure 1 is a rear view of a union suit embodying the invention, the suit being shown as laid out flat; Fig. 2 is a view similar to Fig. 1, but with the large flap folded over to show the crotch construction; Fig. 3 is a front view of the garment shown in Fig. 1; Fig. 4 is a fragmentary front view of the garment without the rear flaps; Fig. 5 is a fragmentary rear view of the garment without the rear flaps; Fig. 6 is a detail of one of the folds at the top of the large flap; Fig. 7 is a detail of the lower part of the rear flap; Fig. 8 is a detail of the small flap; and Fig. 9 is a perspective view of a detail showing the arrangement of the reinforcement for the button-hole in the rear flap.

Referring to the drawings, 10 indicates the body of the garment which is preferably formed from a section of knitted tubular fabric, the wales of which run lengthwise of the garment to give elasticity sideways so that the garment will conform to the shape of the body of the wearer.

In Figs. 1, 2 and 3 I have shown the leg portions of the garment slightly separated in order to better illustrate the construction of the garment. The leg portions 11 and 12 are preferably formed by making a central V-shaped cut 13 in the tubular section, from the bottom to the point 14 which is a short distance below the crotch 15. From the point 14 the front side of the tubular section is cut lengthwise to the neck and the portion of said cut above the crotch 15 has the edges finished in any desirable manner

and closed by fastening means, such as the buttons 16. From the point 14 the rear of the tubular section is cut lengthwise to a point 17, preferably near the waist line. 60

The upper part of the garment may be formed in any preferred manner, but as the construction thereof, illustrated, forms no part of the present invention, a detailed description thereof is deemed unnecessary. 65

The edges of the leg portions 11 and 12 are sewed together from the bottom to the point 14. Above the point 14 the edges of the leg portions are sewed to flaps arranged in a manner about to be described. In order to effectively cover the opening, at the rear of the garment, which extends from the point 14 to the point 17, I provide a large flap 18, which preferably consists of an upper section 19, having a plurality of folds (I prefer to use two such folds) arranged with the wales of the fabric running crosswise of garment, and a lower section 20 having the wales running lengthwise of the garment. The folds 19 are sewed together along the edges 21 and 22 and their lower edges 23 are sewed to the upper edge 24 of the section 20. The upper edge 22 of the flap is sewed to the body of the garment along the line 25 and the edges 26 and 27 75 of the sections of the flap are sewed to the edge 28 of the opening extending from the point 14 to the point 17. 80

From Figs. 6 and 7 it will be seen that the edges 26 and 27 of the sections of the flap are slightly curved for the purpose of giving fullness to the flap. The lower edge 29 of the section 20 of the flap is turned under and sewed along the front edge 30 of the leg, this edge extending from the point 14 95 to the crotch 15. The side edges 21 and 31 of the sections 19 and 20, respectively are cut on a curve, as shown in Figs. 6 and 7, in order to give especial fullness to that portion of the flap which is intended to overlie 100 the buttock of the wearer and permit the free edge of the flap to be positioned along the side of the thigh of the wearer. In order to prevent the section 19 of the flap from stretching at its free edge, I secure 105 along said edge a strip 32 of comparatively inelastic material such as tape. When desired, the flap may be provided with a button-hole 33 which is adapted to receive a button 34, secured to the body of the garment, for the purpose of positively securing 110 the flap in closed position. The peculiar

construction of flap 18, however, tends to make the same self retaining, thus rendering a button, as usually required at this point in garments as heretofore made, unnecessary.

- 5 By having the upper section 19 of the flap made of two folds, the button-hole 33 may be conveniently reinforced by means of a small piece of comparatively inelastic fabric, such as satine, 35, which is arranged between the folds, where it is concealed, and is stitched and fastened by the button-hole stitching. In the stitching which secures the sections 19 and 20 together, the edge 24 of the section 20 is preferably arranged between the folds of the section 19, in order to provide a neat and effective seam.

From the construction of the flap, above described, it will be seen that it will conform to the shape of the wearer's posterior, because the upper section 19 will give elasticity lengthwise, owing to the fact that the wales thereof run crosswise, and the lower section 20 which is arranged over the buttock will be elastic crosswise, owing to the fact that the wales thereof run lengthwise. Since the fabric is comparatively inelastic in the direction of the wales and the free edge 21 of the section 19 is made inelastic by means of the tape 32, it will be apparent that the free edge of the flap is comparatively inelastic throughout its entire length and therefore, as the interior portion of the flap is elastic in both directions, it will conform to the wearer's posterior and the free edge be arranged along the side of the thigh and hold the flap in closed position. When the wearer assumes a stooping or sitting posture, the section 19 of the flap will stretch and thereby render the garment comfortable for all positions of the wearer, while at the same time causing it to closely conform to the body of the wearer. By having the wales of the lower section run lengthwise, I also avoid, to a large extent, the possibility of having the flap become stretched and loose, due to a permanent stretching of the fabric.

From Fig. 7 it will be observed that the edge 29 of the section 20 is cut on a curve of comparatively short radius and when sewed to the edge 30, this produces a fullness 36 in the leg portion 12 of the garment, which is adapted to act as a suspensory, thereby enhancing the health and comfort of the wearer. In order to fully close the crotch of the garment and also construct the leg portion 11 of the garment similar to the leg portion 12, I have provided a small flap 37, the lower portion of which is formed substantially the same as the lower portion of the section 20 of the large flap, but which has its upper edge 45 cut on a diagonal, as shown in Fig. 8. The edge 38, which, as shown in Fig. 8, is cut slightly on a curve to give special fullness at this point, is sewed

along the edge 39 from the point 14 to the point 40. The edge 41 of the flap 37 is sewed along the edge of the garment, which extends from the point 14 to the crotch 15, the corner 43 of the flap being arranged at 70 the point 14 and the edge 44 of the flap may, if desired, be secured to the edge 31 of the section 20 of the large flap, at the crotch, for the purpose of making a closed crotch. If an open crotch is desired, this part can be simply left unfastened, thus making this garment most desirable as being readily made into either a closed or open crotch as the trade may demand. The edge 39 above the point 40 may be finished 80 in any desired manner. The edge 45 of the flap 37 is by this arrangement left free and may be edged or hemmed in the usual manner, and the curved edge 41 provides a fullness 46 in the leg portion 11 of the garment, which is similar to the portion 36 of the leg portion 12. The advantages of thus having both sides similarly constructed will be obvious.

It will be understood that instead of constructing the section 19 of the large flap of a plurality of folds I may use a single fold of comparatively heavy fabric, but I prefer to use a plurality of folds as by this means I may use the same material for this section 95 of the flap as is used for the section 20 and the other portions of the garment. It will also be understood that various other minor changes may be made in the construction of the garment, within the scope of the claims, 100 as I claim broadly a flap having sections with the wales of one section running at an angle to the wales of another section and with the free edge of the flap substantially inelastic lengthwise, for the purpose described.

Having thus described my invention, what I claim is:

1. A garment having an opening therein, and a flap arranged to cover said opening, 110 said flap comprising two fabric sections having their adjoining edges secured together and with the wales of one section extending at an angle to the wales of the other, said flap also having one of its longitudinal 115 edges along both fabric sections secured to the body of the garment and the opposite edge thereof free, and means for rendering said free edge substantially inelastic throughout its entire length.

2. A garment having an opening therein and a flap arranged to cover said opening, said flap being secured to the garment along an edge extending lengthwise of the garment, and having the opposite edge thereof 125 free, and comprising two fabric sections secured together along their adjoining edges, with the wales of one section extending crosswise of the garment and the wales of the other section extending lengthwise of 130

the garment, and the free edge of the flap being substantially inelastic.

3. A garment having an opening therein and a flap arranged to cover said opening, 5 said flap being secured at the top and along an edge extending lengthwise of the garment, and having a free edge extending lengthwise of the garment, and comprising an upper fabric section having 10 the wales thereof extending crosswise of the garment and provided with means for rendering the free edge thereof substantially inelastic, and a lower fabric section having the wales thereof extending 15 lengthwise of the garment.

4. A garment having an opening therein and a flap arranged to cover said opening, said flap being secured at the top and along an edge extending lengthwise of the garment, 20 and having a free edge extending lengthwise of the garment, and comprising an upper fabric section having a plurality of folds with the wales thereof extending crosswise of the garment and provided with 25 means for rendering the free edge thereof substantially inelastic, and a lower fabric section having the wales thereof extending lengthwise of the garment.

5. A garment having a central longitudinal slit in the back thereof, said slit extending a short distance down the inner side of both leg portions, an elongated four-sided flap having one of its longitudinal edges secured along one edge of said slit and the 35 back edge of one of said leg portion slits, and its other longitudinal edge free, and having its upper edge secured across the back of the garment, and its lower edge convexly curved and secured along the front 40 edge of said leg portion slit, a substantially triangular flap having one edge secured along the back edge of the other of said leg portion slits and a portion of the other edge of said back slit, the lower edge of said triangular flap being convexly curved and secured 45 along the front edge of said last-mentioned leg portion slit, as and for the purpose described.

6. A garment having a central longitudinal slit in the back thereof extending a short distance down the inner side of one of the leg portions, an elongated four-sided flap having both of its longitudinal edges convexly curved and one of said edges secured 50 along one edge of said slit, and the other of said edges free, the upper edge of said flap being secured across the back of the garment, and the lower edge thereof being convexly curved and secured along the front 55 edge of the slit in the leg portion of the garment, said flap having a section thereof 60

with wales of the fabric extending crosswise of the garment and another section with the wales of the fabric extending longitudinally of the garment, and the free edge of 65 the flap being substantially inelastic, as and for the purpose described.

7. A garment having an opening therein and a flap arranged to cover said opening, 70 said flap comprising two fabric sections, one of which has a plurality of folds, with the wales thereof extending crosswise of the flap, and a substantially inelastic free edge, and the other of which has the wales extending lengthwise of the flap, said fabric 75 sections being secured together along their adjoining edges, said garment having a button on the body thereof and said flap having a button-hole therein extending through 80 said plurality of folds, and a reinforcement for said button-hole arranged between said folds and secured in position by the button-hole stitching.

8. A garment having a longitudinal opening in the back thereof, a self-retaining flap 85 secured along one edge of said opening and adapted to close the same and having its upper edge secured to the back of the garment, said flap consisting of a plurality of fabric sections arranged with the wales of 90 one section running at an angle to the wales of another section, whereby the flap as a whole is rendered elastic in all directions, and said flap also having a substantially inelastic convexly curved free edge running 95 lengthwise of the garment and adapted to be arranged at the side of the wearer's posterior, substantially as described.

9. A garment of the class described, having a longitudinal opening in the back thereof, 100 a self-retaining flap secured along one edge of said opening and adapted to close the same and having its upper edge secured to the back of the garment, said flap consisting of a plurality of fabric sections with 105 the wales of one section running crosswise of the flap and the wales of another section running lengthwise of the flap, whereby the flap, as a whole, is rendered elastic in all directions, and said flap also having a substantially inelastic convexly curved free edge running 110 lengthwise of the garment and adapted to be arranged at the side of the wearer's posterior, substantially as described.

115 In testimony whereof I affix my signature in presence of two witnesses.

WILLIAM H. BILBROUGH.
